Primary Examiner—Holly H. Baynam*Assistant Examiner*—Cynthia M Chin*(74) Attorney, Agent, or Firm*—Adriana S. Luedke; Dorsey & Whitney LLP(57) **CLAIM**

The ornamental design for an interconnecting block, as shown and described.

DESCRIPTION

FIG. 1 is a perspective view of an interconnecting block showing my new design;

FIG. 2 is a top view thereof;

FIG. 3 is a front view thereof;

FIG. 4 is a right side view thereof;

FIG. 5 is a left side view thereof;

FIG. 6 is a rear view thereof; and,

FIG. 7 is a bottom view thereof.

The broken lines are for illustrative purposes only and form no part of the claimed design.
